UNITED STATES PATENT OFFICE.

FRANKLIN L. LANE, OF BELOIT, WISCONSIN, ASSIGNOR TO THE BERLIN MACHINE WORKS, OF BELOIT, WISCONSIN, A CORPORATION OF WISCONSIN.

ABRADING-CYLINDER.

1,030,897.

Specification of Letters Patent.

Patented July 2, 1912.

Application filed March 7, 1910. Serial No. 547,679.

To all whom it may concern:

Be it known that I, FRANKLIN L. LANE, a citizen of the United States, residing at Beloit, in the county of Rock and State of Wisconsin, have invented certain new and useful Improvements in Abrading-Cylinders, of which the following is a specification.

My invention relates to abrading cylinders and has special reference to a regulating mechanism for adjusting the clamping disks placed at each end of the abrading cylinder.

In Patent No. 577,582, issued Feb. 23, 1897, to F. L. Lane and H. J. Mitchell, a form of abrading cylinder was disclosed which has much the same general characteristics as the cylinder which is used in my present invention. It will be noticed however, that in the form of cylinder described in the above mentioned patent, the clamping disks or rings are moved simultaneously by suitable mechanism and no provision is made for moving these disks independently of each other. When the abrading material in the form of sand-paper, emery cloth or the like is spirally wrapped around the cylindrical shell, the ends are attached to the clamping disks. In order to tighten the abrading material on the cylindrical shell, mechanism is provided by which these disks can be moved in a longitudinal direction away from the cylindrical shell. It is evident that if the two clamping disks are moved in a straight longitudinal direction, the abrading material would be somewhat wrinkled by such movement inasmuch as the same is wrapped or wound about the cylindrical shell in a spiral manner. Each disk is provided with a slotted lug projecting inwardly toward the main cylindrical shell, the slot in this lug engaging a pin mounted on the inside of the cylinder. I preferably form this slot in an oblique direction so that the two disks when being moved in a longitudinal direction are at the same time rotated to give the proper pressure on the abrading material and prevent the same from becoming wrinkled. This general system of operation which I have just described is disclosed in the above mentioned patent, but as previously stated, no provision is made by which the two clamping disks can be moved independently of each other. Inasmuch as it is often desired to apply tension on the abrading mate-

rial to a greater extent toward one end of the cylinder than the other, I have found it of very great advantage to use a mechanism for obtaining such an independent movement of the two clamping disks. It is especially desirable to have such independent adjustment after the cylinder has been operated for some time as there is a strong tendency for the abrading material to become loose on the end of the cylinder toward which the spirally wound material is forced by the pressure of the object which is being abraded. It is the mechanism which attains this independent adjustment of the clamping disks which forms the subject matter of my present invention.

By reference to the above mentioned patent to Lane and Mitchell, it will be observed that the two clamping disks are operated by means of gears which have threaded engagement with the disks and that these gears are operated by means of pinions in mesh with the same, the two pinions being rigidly mounted on a shaft. In order to cause the two clamping disks to be moved in opposite longitudinal directions when the two gears associated therewith are rotated in the same direction, the pitch of the threads of the two gears is in opposite directions, that is, a left-hand thread is used in connection with one gear and a right-hand thread in connection with the other. Instead of having the two pinions above mentioned rigidly mounted on their shaft, as in the case of the previously mentioned patent, in my present invention I have one pinion rigidly mounted on the shaft and the second pinion is loosely mounted thereon, having threaded engagement with the shaft and the parts are so constructed that when the pinion is rotated or screwed into a predetermined position on the shaft, a shoulder or clutch member on the pinion engages a similar co-operating member on the shaft and thus if the pinion is rotated in one direction it will simultaneously rotate the shaft, whereas if the shaft is rotated in the opposite direction it will simultaneously rotate the pinion. The construction of the parts is such that, as will be described in detail hereafter, when the two clamping disks are in their normal positions nearest to the cylindrical shell, if the shaft on which the two pinions are mounted is rotated, the loosely mounted pinion is engaged by the clutch member on the shaft

and thus both pinions are rotated causing both clamping disks to be moved in a longitudinal direction away from the main cylinder. On the other hand, if it is desired to move only one of the clamping disks, this result may be accomplished by engaging a suitable key with the loosely mounted pinion and rotating this pinion independently of the shaft on which it is mounted. After the associated disk has been moved to its proper position the key engaging the pinion may be withdrawn and a second key engaging the shaft may be placed in position and the second clamping disk may then be moved to its desired position.

Although I have just described a somewhat specific embodiment of my invention, the fundamental object is to obtain an independent adjustment of the two clamping disks, such adjustment preferably being operable from one end of the abrading cylinder, and many departures can be made from the exact construction which is disclosed herein without departing from the spirit of my invention.

A preferred embodiment of my invention is described in the accompanying drawings in which,

Figure 1 is a plan view of the abrading cylinder with the disks in position. Fig. 2 is an enlarged vertical longitudinal section through the ends of the cylinder and their associated parts. Fig. 3 is an end elevation of the main cylinder. Fig. 4 is an end elevation of one of the clamping disks. Fig. 5 is an enlarged perspective view of the loosely mounted adjusting pinion. Fig. 6 is an enlarged perspective view of the portion of the shaft on which the adjusting pinion is mounted. Fig. 7 is an enlarged perspective view of the key which is adapted to operate the loosely mounted pinion.

On the cylindrical shell 11 is spirally wound the abrading material 12, the edges of which are lapped along the line of the spiral groove 13 in the shell 11. Near each end of the shell 11 is a cylinder head 14, having a hub 14^a through which the main shaft 15 passes. The cylinder heads 14 are located a sufficient distance from the ends of the cylinder shell to form recesses for containing the various operating parts which will be described hereafter.

A clamping disk or ring 16 is provided at each end of the cylindrical shell 11, and has a hub 17 which is mounted on the main operating shaft 15. The periphery of each clamping disk 16 is continuous with the periphery of the cylindrical shell 11. Loosely mounted on the outer portion of the hub 17 is a bell crank lever 18, which has the arm 19 with a slotted opening 20, the screw 21, inserted in the body of the clamping member 16, acting as a detent for the bell crank lever 18. The arm 19 is provided with a

shouldered end 22 which is engaged by the hooked end 23 of the clamping band or strap 24, which encircles the clamping disk 16. A portion of the periphery of the disk 16 is cut away forming the opening 25 and the hooked end 26 attached to the strap 24 is secured to the shoulder 27 on the periphery of the clamping ring 16.

A lug 28 is mounted on the clamping disk 16, and through this lug passes the set screw 29 which engages the portion 30 of the bell crank lever 18. It is now evident that by adjusting the set screw 29, the tension of the clamping strap 24 may be regulated as desired.

The portion of the hub 17 which lies toward the cylindrical shell is provided with threads which engage similar threads on the inside of the sleeve portion 31 of the gear 32, this gear being mounted on the hub 14^a of the cylinder head 14. The hub of the clamping disk on one end of the cylindrical shell is provided with left hand threads, whereas that on the other end is provided with right-hand threads, in order to cause movement of the clamping disks in opposite directions, as will be described hereafter. The headed screw 33 is mounted on the cylindrical head 14 and is for the purpose of preventing longitudinal movement of the gear 32.

Mounted within the cylindrical shell 11 and having its bearings in the cylinder heads 14-14, is the adjusting shaft 34, on one end of which is rigidly mounted the pinion 35, in mesh with its corresponding gear 32. Also rigidly mounted on the shaft 34 is the collar or clutch member 36 provided with the shoulder 37, which is adapted to engage the shoulder 38 of the pinion 39 which is loosely mounted on the shaft 34 and has threaded engagement therewith. This pinion 39 has a hub 40 with slots 41 adapted to form engagement with the projections 42 on the key 43, which may be inserted through the opening 44 in the left-hand clamping disk 16 as shown in Fig. 2. The left-hand end of the shaft 44 is formed into a key stud 45 which may be engaged by a suitable key when the key 43 is withdrawn. Projecting inwardly from each of the clamping disks 16, is the lug 46 which has an oblique slot 47 engaging the pin 48 mounted on the inner face of the cylindrical shell 11. Two of these lugs 46 are preferably provided in connection with each clamping disk.

Having thus described the construction of the parts used in my invention, the operation of the same may now be readily understood: The abrading material 12 is fastened to the right-hand clamping disk 16 and is spirally wound around the cylindrical shell 11, and is cut off so that its ends project over the left hand end of the shell 130

11. The left-hand edges of the abrading material which are thus formed are secured to the left-hand clamping disk 16, by means of the clamping strap or band 24. Now let us assume that it is desired to move both of the clamping disks 16 outwardly in a longitudinal direction and at the same time partially rotate them, as is usually the case when the abrading material is first put on.

10 A key is inserted through the opening 44 in the left-hand clamping disk 16, and engages the key stud 45, the key is turned in a clockwise direction, the shaft 34 is rotated thereby and the shoulder 37 engages the shoulder 38 on the pinion 39. In this way both the pinion 39 and the pinion 35 are rotated, communicating their motion to the gears 32 which are rotated in a contra-clockwise direction. The hubs 17 of the 20 clamping disks 16 having threaded engagement with the sleeve portions 31 of the gears 32, both of the clamping disks are forced outwardly being prevented from rotation with the gears 32 by means of the pins 48, but being guided in their movement by these pins and if the slots 47 are oblique, the two 25 clamping disks are thereby given a partial rotation. If it is now desired to return these clamping disks to their original positions, the key engaging the key stud 45 is withdrawn and the key 43 is inserted through the opening 44, and engagement is formed with the pinion 39. This pinion is now rotated in a contra-clockwise direction and the shoulder 38 engages the shoulder 37 of the collar 36 and both the pinions 39 and 35 are consequently rotated, and as will be 30 readily understood, the clamping disks are returned to their original position.

40 After the abrading cylinder has been used for some time it may be desired to move the left-hand clamping disk 16 and to leave the right-hand clamping disk stationary. The key 43 is engaged with the pinion 39 and this pinion is rotated in a clockwise direction, the shoulder 38 leaving its engagement with the shoulder 37 on the collar 36. The pinion 39 is gradually moved to the left by means of its threaded engagement with 45 the shaft 34 and the gear teeth of the pinion slide along on the gear teeth of the gear 32 but remain in mesh therewith. After the left-hand clamping disk 16 has been adjusted as desired, the right hand clamping 50 disk may be moved by withdrawing the key 43 and using the key which engages the key stud 45 on the shaft 34, this shaft being rotated in a clockwise direction and thus communicating the motion to the right-hand 55 clamping disk 16 through the pinion 34 to the gear 32 with which it is in mesh. The two clamping disks may be returned to their original positions either independently by successively rotating the shaft 34 and the 60 pinion 39 in a contra-clockwise direction, or

by rotating the pinion 39 in a contra-clockwise direction until the shoulder 38 engages the shoulder 37, after which the movement of the two clamping disks will be simultaneous.

Having thus described my invention what I claim and desire to cover by United States Letters Patent is:

1. In a device of the class described, the combination of a main cylindrical member having abrading material wound thereon, end members longitudinally movable with respect to said cylindrical member and to which said abrading material is attached, and means for moving said end members independently of each other and of the cylindrical member, the movement of said end members in a direction away from the said cylindrical member causing the tightening of the abrading material.

2. In a device of the class described, the combination of a main cylindrical member having abrading material wound thereon, end members longitudinally movable with respect to said cylindrical member and to which said abrading material is attached, and means for selectively moving said end members simultaneously or independently of each other.

3. In a device of the class described, the combination of a cylindrical shell having abrading material wound thereon, a longitudinally movable clamping disk at each end of said cylindrical shell and to which said abrading material is secured, and means for moving said clamping disks independently of each other, and of the cylindrical shell.

4. In an abrading cylinder, the combination of a cylindrical shell having abrading material wound thereon, a clamping disk at each end of said shell and to which said abrading material is secured, a gear having threaded engagement with the hub of each of said clamping disks, a pinion in mesh with each of said gears, means for limiting the rotation of each clamping disk thereby causing longitudinal movement of the disk when its associated gear is rotated, and means for selectively rotating said pinions either simultaneously or independently of each other.

5. In an abrading cylinder, the combination of a cylindrical shell having abrading material wound thereon, a clamping disk at each end of said shell and to which said abrading material is secured, a gear associated with each of said clamping disks and having threaded engagement therewith, a pinion in mesh with each of said gears, a shaft on which one of said pinions is rotatably mounted and with which the second pinion has threaded engagement, and a clutch member on said shaft adapted for engagement with said second pinion, said pin-

ions adapted to be simultaneously rotated when said clutch member engages said pinion and to be independently rotated when said second pinion is moved out of engagement with the clutch member on said shaft.

- 5 6. In an abrading cylinder, the combination of a clamping disk at each end of the cylinder, a rotatable member associated with each disk for causing longitudinal movement of said disks in opposite directions when said members are rotated in the same direction, and means for selectively rotating said members simultaneously or independently of each other.
- 10 7. In an abrading cylinder, the combination of a clamping disk at each end of the cylinder, a rotatable gear associated with each of said clamping disks and having threaded engagement therewith, the pitch 20 of the threads of said gears being in opposite directions thereby causing said disks to be longitudinally moved in opposite directions when the said gears are rotated in the same direction, a shaft mounted within said 25 cylinder, a pinion rigidly mounted on said shaft and in mesh with one of said gears, and a second pinion loosely mounted on said

shaft and in mesh with the other of said gears, said second pinion and said shaft adapted to be rotated independently of each other.

8. In an abrading device, the combination of a main cylindrical member, a clamping disk at each end of said member, a gear associated with each clamping disk and having threaded engagement therewith, a shaft mounted within said cylinder, one end of the shaft formed into a key stud, a pinion rigidly mounted on said shaft and in mesh with one of said gears, and a second pinion 40 having threaded engagement with said shaft and in mesh with the second gear, said second pinion adapted to be engaged by a key and having a shoulder portion adapted to engage a similar shoulder portion on said shaft when rotated to a predetermined position, said shaft and second pinion adapted for simultaneous rotation when said engagement is preserved and for independent rotation when said engagement is broken.
